UNITED STATES PATENT OFFICE.

ANNA MCKEVIT, OF CHICAGO, ILLINOIS.

BUTTON AND BUTTON-FASTENER.

SPECIFICATION forming part of Letters Patent No. 272,736, dated February 20, 1883.

Application filed November 13, 1882. (No model.)

To all whom it may concern:

Be it known that I, ANNA MCKEVIT, residing at Chicago, in the county of Cook and State of Illinois, and a citizen of the United States, have invented a new and useful Improvement in Button Stems and Fasteners, of which the following is a full description, reference being had to the accompanying drawings, in which—

10 Figure 1 is a side elevation, showing a button and fastener embodying my invention secured to a piece of cloth. Fig. 2 is a vertical longitudinal section of the same. Fig. 3 is a detail, being a vertical section of the nut. Fig. 4 is a detail, being a vertical section of the collar. Fig. 5 is a vertical section, showing the button with the fastening-stem, the collar and nut being removed.

15 I have recently applied for Letters Patent of the United States for an improvement in button stems and fasteners, and my present invention may be regarded as an improvement in the devices therein described.

This invention is designed as an improvement upon the invention patented by me January 2, 1883, No. 269,870, its object being to lessen the cost of production and produce a strong and durable separable button, one in which the least number of detachable parts is employed.

The invention consists in the peculiar construction and combination of parts constituting the separable button, the combination consisting of a button or head, a screw-stem, a recessed collar, and an under button or flanged nut having a boss for entering the recess in the collar, said under button or nut and its boss having a central screw-threaded opening for connecting with the stem of the button.

40 In the drawings, *a* represents the body of a button, which may be made of metal or any other suitable material.

b is a stem, one end of which may be permanently secured to the body *a* of the button either by riveting, soldering, or any other known suitable manner. The other end of this stem *b* is screw-threaded, and the extreme end is pointed, so that it can be readily forced through cloth.

50 *c* is a collar, the periphery of which is con-

cave. One side of the collar is flat or otherwise shaped so as to fit against the inside of the body *a*. In the other side of this collar is a recess, *d*.

e is a nut having upon one side a long flange or boss, *f*, which is screw-threaded upon the inside and adapted to fit the screw-threaded stem *b*. The extremity of this flange *f* should be tapering or pointed, as shown in the drawings, so that it can readily pass through the cloth.

g represents a piece of cloth to which the button is secured.

The collar *c* can most conveniently be made separate from the stem and detachable therefrom; but, if desired, it might be permanently secured to the stem.

To secure this button to a garment or other article the collar, if detachable from the stem, is to be first placed upon the stem. Then that portion of the stem which projects beyond the collar is to be forced through the cloth. Then the nut is to be applied, the flange of the nut passing through the cloth, and the end of the flange passing down into the recess *d* in the collar *c*. I thus provide for the button-fastener a nut having a long screw-threaded holding-surface without increasing the thickness of that portion which comes in contact with the cloth, and although the cloth may vary considerably in thickness the button will be held firmly in place, and the inside of the nut will have a sufficient screw-threaded bearing. The concave periphery of the collar *c* furnishes a smooth and desirable surface for a button-hole.

I do not confine myself to the use of a stem permanently secured to the body of the button. The end of the stem which enters the body of the button might be made screw-threaded in cases where the body of the button was adapted to receive the same; but I make no claim for this construction. If desired, all of that portion of the stem which projects beyond the body of the button might be screw-threaded, and the collar could be screw-threaded upon the inside correspondingly.

By making the flange or boss *f* upon the nut tapering it not only passes easily through the cloth, but in case any thread should be carried along into the recess in the collar there

will be a little space between the lower end of the flange and the wall of the recess for such thread.

I do not limit myself to a collar which has a concave periphery, but consider that form the best.

For convenience a large button is shown in the drawings; but the improvement can be used with buttons of various sizes.

10 What I claim as new, and desire to secure by Letters Patent, is as follows:

The combination, in a separable button, of

the button or head *a*, a screw-stem, *b*, recessed collar *c*, and under button or flanged nut having a boss for entering the recess in the collar, 15 said under button or nut and its boss having a central screw-threaded opening for connecting with the stem of the button, substantially as and for the purpose set forth.

ANNA McKEVIT.
